CLAIM

The ornamental design for a charging case, as shown and described.

DESCRIPTION

This application is related to Application Ser. No. 29/730, 537, entitled Earbud Charging Case, which is concurrently filed herewith, and the disclosure of which is incorporated herein by reference. This application is also related to Application Ser. No. 29/709,173, entitled Wireless Earbud, and Application Ser. No. 29/709,177, entitled Charging Case, both filed on Oct. 11, 2019, the disclosures all of which are incorporated herein by reference.

FIG. 1 is a front perspective view of the charging case according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings depict portions of the charging case that form no part of the claimed design.

(Continued)

The dash-dot-dash lines define the boundaries of the claim and form no part of the claimed design.
